HAIR CLIPPER

Substitute for abandoned application Serial No. 632,221, filed April 16, 1923. This application filed April 14, 1927. Serial No. 185,334.

This invention relates to hair clippers intended for use by an individual for cutting his own hair, as distinguished from the well known types of clippers intended for use by barbers. This application has been substituted for applicants' abandoned application for patent for hair clippers, filed April 16, 1923, Serial No. 632,221.

Considered in its more specific aspects, another object of this invention is to improve upon the means for automatically and progressively varying the distance of the cutting knives from the head as the clipper is actuated.

For the accomplishment of these and such further objects as will hereinafter be apparent to those skilled in the art to which this appertains, the invention consists in the construction, combination and arrangement of parts herein specifically described and illustrated in the accompanying drawings, wherein is shown a preferred embodiment of the invention, but it is to be understood that changes, variations and modifications may be resorted to which fall within the scope of the claims hereunto appended.

In the drawings forming a portion of this specification,

Fig. 1 is a section on the line 1—1 of Fig. 2.

Fig. 2 is a section on the line 2—2 of Fig. 1.

Fig. 3 is an enlarged section on the line 3—3 of Fig. 1.

Fig. 4 is a front elevation.

Fig. 5 is a section on the line 5—5 of Fig. 1.

Fig. 6 is a perspective of an adjustable guiding means to be used in connection with our hair cutting device, showing the manner of attaching the guides to the head of the user, the outline of the head being shown in dotted lines.

Fig. 7 is an enlarged section through the connection of the horizontally extending guide to the transverse guides, and

Fig. 8 is a top view of the structure shown in Fig. 7.

As shown in the drawings, a base plate 10 has extending upwardly therefrom, a yoke 11, the arms 12 of which act as guides for engagement by the notches 13 cut into the sides 50 of the lower cutting knife 15. The lower

cutting knife is provided at its center with an aperture 16 through which passes the block 17, having the enlarged head 18 at the base thereof. Pins 17^a project outwardly from the block 17 and engage in suitable notches in the knife to prevent the block from turning. The block 17 is cut away as indicated at 19 to receive the boss 20 of a handle 21 which is pivoted upon the pin 22 received in a suitable hole drilled through the center of the block and serving as a pivot for the handle 21.

A tongue 23 projects radially from the boss 20 of the handle 21 and is bent downwardly to engage a slot 24 in the upper cutting knife 25 which is dovetailed as at 26 to a similar knife 27. The knives 15, 25 and 27 are provided with comb-like cutting teeth in the usual manner of devices of this character. A torsion spring 28 is coiled around the pin 22 and has one of its ends anchored to the block 17 and its other end in contact with the tongue 23 to normally urge the handle 21 away from the handle 29.

Slidably mounted in a small boss 30 fixed to the underside of the handle 21 is a pawl 31 normally held by the spring 32 in contact with the toothed circumference of a ratchet wheel 33. The ratchet wheel 33 is fixed upon the lower end of a screw 34 and is rotatably received in a socket 35 in the upper end of the block 17. A screw cap 36 is threaded onto the threaded reduced upper end of the segmental bushing 9 and engages against the upper face of a cup-shaped housing 37 and clamps the housing against the shoulder 38 of the bushing 9.

The handle 29 is preferably integral with the housing 37 and the parts are so proportioned that when the housing is engaged by the cap screw 36, its lower face will contact with the knives 25 and 27 to hold them neatly in sliding engagement with the lower knife 15.

The knives 25 and 27 are provided with the slots 38' in which the lugs 39 projecting upwardly from the lower knife 15 engage to hold the upper knives against horizontal displacement. The central portion of each of the knives 25 and 27 is cut away as indicated at 40, and the outer side edges are cut away 100

as at 41 to provide sufficient clearance to permit the knives to reciprocate.

Slidably mounted on the yoke 11 are the members 42 of a split nut, having the apertures 43 therein to receive the inner ends of members 44 which are secured to the handles 45. The latter are slidably mounted in the elongated slots 46, springs 47 being provided to normally hold the halves of the nut in engagement with the threads of the screw.

Guiding means are provided to be attached to the user's head when it is desired to use the device and said means comprises the spring clamps 50 adapted to be engaged over the top of the head and the neck of the user. These clamps comprise upper and lower spaced members 51 and 52 between which the ends 53 of the vertical guide 54 are slidably received. The upper member 52 is provided with a slot 55 having a plurality of spaced notches 56 therein which notches are adapted to be engaged by the headed pin 57. The guide 54 is provided along one edge with the upwardly extending flange 58 against which the side of the clipper is placed when in use.

The operation of the device is as follows: the handles 45 are pressed inwardly to release the split nut 42 and the screw carrying the knives 15, 25 and 27 with it is moved downwardly until the knives contact with the base plate 10. If it is desired to cut the hair on the back of the head, the cut is preferably started at the neck and as the handle 21 is operated, the pawl 31 will cause the screw 34 to be automatically actuated to gradually move the knives away from the base plate thereby varying the depth of the cut in a manner which will be obvious. If desired the cut could be started at the top and worked downwardly, the knives being raised to the desired height and the pawl 31 turned in the direction to cause the knives to move downwardly. To insure that the whole surface of the back portion of the head may be cut, the guides shown in Fig. 6 are used, the clips 50 are placed over the top of the head and the neck respectively and the edge of the clipper is held against the flange 58 of the guide 54, while making a cut. After each cut is completed, the guide 54 is moved until the pins 57 engage the adjacent notches 56, the distance between the notches being less than the width of the clipper.

We claim:

1. A hair clipper intended for cutting the hair of the user thereof comprising a base plate, a yoke mounted on said base plate, a nut carried by said yoke, a screw mounted in said yoke, a lower knife, an upper knife, slidably mounted on said lower knife, a block passing through said lower knife, a recess in the upper face of said block, a ratchet wheel secured to the base of said screw and rotatably mounted in said block, a pair of handles for moving said upper knife transversely

across said lower knife, a pawl carried by one of said handles to engage said ratchet wheel, a housing substantially enclosing said block, and means for clamping said housing to said block.

2. A hair clipper comprising a base plate, a pair of cutting knives, guiding means adapted to permit said knives to be moved relatively to said base plate and parallel thereto, the lower knife being immovable save in a direction towards and away from said base plate, said lower knife having a central recess, a block located in said recess and having an enlarged head below said recess and engaging said lower knife, a handle connected to said lower knife, another handle pivotally mounted on said block above said lower knife, connecting means intermediate said block and the upper knife, a ratchet mounted in said block above said upper knife, means connected to the handle of the upper knife and adapted to intermittently engage and turn said ratchet, and means actuated by said ratchet to move said knives relatively to said base plate.

3. In a hair clipper, a base plate having a U-shaped yoke, a pair of knives mounted upon the upstanding arms of said yoke, a screw passing through the top arm of said yoke and connected to said knives, a split nut mounted upon said screw, means located at the top arm of said yoke and adapted to separate the halves of said split nut, handles for said knives, and means actuated by the movement of one of said handles and adapted to turn said screw relatively to said split nut.

4. In a hair clipper, the combination with a pair of relatively movable upper and lower knife plates, of a segmental housing, a threaded bushing above said plates and passing through the upper end of said housing, a block member supporting said bushing, a nut threaded to said bushing and forcing said housing against the upper knife plate, a screw rotatably supported by said member, a movable handle pivoted to said member, means for operatively connecting said handle to said screw for rotating said screw, and means for operatively connecting said handle to said upper knife plate to move said knife plates relatively, said housing enclosing the lower part of said screw and both of said aforementioned means.

5. A hair clipper comprising a base plate having a yoke connected thereto, said yoke having upstanding arms, a pair of knives arranged one above the other engaging and guided by said arms, and maintained by said arms against rotation relatively to said base plate, a headed block passing through said knives and arranged with the head thereof below the lower knife, a movable handle pivoted to said block and means operatively connected to said handle and entering said

block for moving said knives vertically relatively to said base plate.

6. A hair clipper comprising a base plate, a pair of knives arranged above said plate and one above the other, a handle in fixed relation to the lower knife, a movable handle pivoted relatively to said knives, and means operatively connected to said handle for moving said knives vertically relatively to said base plate, comprising a screw, a ratchet wheel secured to the lower end of said screw, a member passing through the knives and headed thereunder, said member receiving and supporting the screw, at one end thereof, carrying a pivot for the end of the movable handle at the other end thereof and being recessed for the reception of said ratchet wheel, and a pawl carried by the movable handle intermediate the ends thereof to engage said ratchet wheel.

7. A hair clipper comprising a base plate, a pair of knives arranged one above the other, a movable handle pivoted relatively to said knives and means for moving said knives vertically relatively to said base plate comprising an upright screw terminating at its lower end above said knives, a ratchet wheel secured to the lower end of said screw, a boss on the handle intermediate the ends thereof, a pawl mounted in said boss, and a coil spring operating on said pawl and engaging said boss for urging said pawl into engagement with said ratchet wheel and a pivot for the end of said movable handle arranged coaxially of said screw.

8. A hair clipper comprising a base plate having a yoke connected thereto, said yoke having upstanding arms, a pair of knives engaging and guided by said arms and having apertures therein, the upper knife being slideable on the lower knife, a handle movable relatively to said knives, a pivot for said handle arranged in the apertures of said knives, and means operatively connected to said handle for moving said knives relatively to said base plate comprising a screw, a ratchet wheel secured to said screw mounted coaxially of said pivot, means including said ratchet wheel to secure said screw to said knives, a pawl carried by said handle to engage said ratchet wheel, and a spring-pressed split nut to enable said screw and knives to be set at various distances from said base plate.

9. In a hair clipper, a pair of knife plates having apertures therein, each having cooperating teeth thereon at each of the ends thereof, a base plate, and means for simultaneously varying the distance of said knife plates from said base plate and relatively reciprocating said knife plates whereby said clipper is operative to cut varying lengths of hair on movement of the clipper in either direction longitudinally of said knife plates, said means including a handle, a pivot for said handle arranged to pass through the

apertures in said knife plates, a boss on said handle intermediate the ends thereof, a spring-pressed pawl carried by said boss, a screw arranged coaxially of the pivot, and a ratchet wheel secured to the lowermost end of said screw and engaged by said pawl and operatively connected to said knife plates.

10. In a hair clipper, a pair of relatively slideable knives, a supporting block passing through said knives, a screw rotatably supported by said block, a handle pivoted to said block, and operatively connected to said screw, a housing enclosing said block, the lower end of said screw, and the pivoted end of said handle, a bushing engaging said block and passing through the upper end of said housing, a screw cap for said housing secured to the upper end of said bushing, and a base plate operatively connected to said screw.
